FURNACE

John A. Ulberg, Sioux Falls, S. Dak.

Application April 25, 1944, Serial No. 532,636

1 Claim. (Cl. 126—99)

This invention relates to furnaces, and has particular reference to improvements in furnaces of the general type comprising an inner shell or casing enclosing a combustion chamber and an outer shell or casing surrounding or enclosing said inner shell or casing and cooperating therewith to define therebetween a chamber wherein air or water is heated by radiation of heat from the combustion chamber for conduction to desired points by suitable pipes or conduits leading from the outer shell or casing.

One special and important object of the invention is to provide a furnace of the general type mentioned embodying an inner shell or casing of novel form designed to afford an exceptionally large heat radiating area whereby high heating efficiency is obtained from fuel consumed in the combustion chamber.

Another special and important object of the invention is to provide a furnace of the general type mentioned embodying an inner shell or casing of novel form and a novel arrangement of the firebox or oil or gas burner or burner nozzle, as the case may be, and of a gas outlet flue, relative to said inner shell and relative to each other, whereby high heating efficiency is obtained from fuel consumed in the combustion chamber.

Another special and important object of the invention is to provide a furnace of the type mentioned embodying the features of the invention and which is of simple practical construction and of low production cost.

With the foregoing and other objects in view, which will become more fully apparent as the nature of the invention is better understood, the same consists in a furnace embodying the novel features of construction, combination and arrangement of parts as will be hereinafter more fully described and defined in the appended claims.

In the accompanying drawing, wherein like characters of reference denote corresponding parts in the different views:

Figure 1 is a perspective view of a furnace constructed in accordance with one practical embodiment of the invention, the outer casing being broken away to show the interior construction.

Figure 2 is a vertical section on the line 2—2 of Figure 1; and

Figure 3 is a horizontal section on the line 3—3 of Figure 2.

Referring to the drawing in detail, it will be observed that the present furnace is of the

general type comprising an inner shell or casing 10 enclosing a combustion chamber a, and an outer shell or casing 11 surrounding or enclosing said inner shell or casing and cooperating therewith to define therebetween a chamber b to contain a fluid, such as air or water, to be heated.

Both of the shells or casings 10 and 11 may be formed in any suitable manner from any 10 suitable material and may be of any desired sizes and shapes. Moreover, any suitable means such as an oil or gas burner 12 or, alternatively, a firebox for burning coal or like fuel may be provided entirely or in part within the combustion 15 chamber a for heating said chamber, and a flue 13 is provided for outlet of combustion gases from said chamber.

Preferably the inner casing 10 and the combustion chamber a are of narrow, elongated 20 form and are upwardly tapered. Preferably, too, the oil or gas burner or firebox 12, as the case may be, is disposed as low as practicable in the combustion chamber a, and the flue 13 is disposed as high as practicable in said combustion chamber, whereby the combustion gases 25 are required to travel substantially from bottom to top of said combustion chamber before they escape therefrom through the flue 13. Moreover, the side walls 14 of the casing 10 preferably are corrugated as indicated at 15 to afford 30 a large area for exchange of heat from the combustion chamber a to the chamber b and said corrugations 15, considered lengthwise, preferably extend vertically so that the upwardly flowing gases may pass freely through substantially all portions of all of the same. Furthermore, the flue 13 preferably extends horizontally or substantially horizontally from end to end of the combustion chamber a and has 35 therein a comparatively narrow, elongated slot 16 extending longitudinally thereof and opening preferably through the top thereof to insure substantially uniform distribution of the combustion gases throughout the combustion 40 chamber. In other words, while the area of the slot 16 preferably is as great as the cross sectional area of the flue 13, said slot preferably is of such narrow width as to preclude the possibility of all of the combustion gases escaping 45 through any short-length portions of the same. Therefore, the combustion gases distribute themselves along the length of said slot, which preferably is substantially co-extensive in length with the combustion chamber a and, as a consequence, the gases are distributed substantially 50 55

evenly throughout the length of said combustion as they flow upwardly therethrough. At the same time due to the narrow width of said combustion chamber, the gases are distributed substantially evenly throughout the width thereof. Moreover, due to the upwardly tapering form of the combustion chamber, the combustion gases are directed inwardly and thereby are concentrated as they rise and lose their heat, with the result that the exchange of heat between the chambers *a* and *b* is substantially uniform throughout the heights of said chambers.

The corrugated side walls 14 of the inner shell or casing 10 may be in direct interfitting engagement with each other at their upper ends where they may be welded or otherwise suitably fastened directly together, or the said upper ends of said side walls may be spaced apart and connected together by a cap-piece 17 to which they may be welded or otherwise suitably fastened. In either case, the end walls 18 of said inner shell or casing may be formed either as integral parts of the side walls 14 thereof, or separately from said side walls to which they may be welded or otherwise suitably secured.

Preferably the flue 13 extends entirely through the chambers *a* and *b* and is closed at one end, exteriorly of the outer shell or casing 11, by a cap 19 which preferably is removable to afford ready access to said flue for the purpose of cleaning the same or for any other desired purpose.

Within the flue 13 may be arranged a pipe or coil 20 to contain water or other fluid to be heated by hot gases flowing through said flue, said coil 20 comprising, for example, part of a hot water supply system of a dwelling or the like and being used particularly when the furnace is of the type in which air is heated in the chamber *b*.

Welded or other suitable joints may be provided between the flue 13 and the shells or casings 10 and 11 at the points where said flue extends through said shells or casings, while at its bot-

tom the shell or casing 10 may be closed in any suitable manner as by a plate 21.

Due to the described construction of the present furnace it has been found that high advantage is obtained from fuel consumed. At the same time, said furnace obviously is of simple construction and may be produced at comparatively low cost.

From the foregoing description considered in connection with the accompanying drawing, it is believed that the construction and operation of the furnace will be clearly understood and its advantages appreciated. It is desired to point out, however, that while only a single specific structural embodiment of the invention has been illustrated and described, the same is readily capable of specifically different structural embodiments within its spirit and scope as defined in the appended claim.

I claim:

20 A furnace comprising a combustion chamber having a bottom wall, end walls, a top wall and upwardly converging corrugated side walls, an outer casing enclosing the combustion chamber in spaced relation thereto so as to define therebetween a chamber to contain a fluid to be heated, means for interiorly heating the combustion chamber, the corrugations of the side walls of the combustion chamber considered lengthwise extending vertically through said top and bottom walls thereof so as to provide for free upward flow of hot gases through the combustion chamber and to afford a large area for exchange of heat from the combustion chamber to said fluid-containing chamber, and a flue for outlet of combustion gases 25 extending through the combustion chamber and wholly supported by the end walls of the latter in spaced relation to the top, bottom and sides thereof, said flue having an elongated upwardly facing slot extending longitudinally thereof, said 30 slot having its ends terminating spaced from the end walls of the combustion chamber for entrance into the same of combustion gases from said combustion chamber.

JOHN A. ULBERG.
